MANUFACTURE OF HIGH OCTANE
GASOLINE

Frank J. Jenny, Forest Hills, N. Y., assignor to
The M. W. Kellogg Company, Jersey City, N. J.,
a corporation of Delaware

Application October 30, 1941, Serial No. 417,054

3 Claims. (Cl. 260—683.4)

This invention relates to the manufacture of high octane gasoline, and particularly to an improved combination of gasoline manufacturing processes including naphtha reforming, butane pyrolysis, and catalytic iso-paraffin-olefin alkylation. The invention has for its principal object the provision of a method of pyrolyzing the non-alkylatable hydrocarbon normal butane to produce the alkylatable hydrocarbon butylene, and of simultaneously thermally reforming a low octane naphtha, wherein the normal butane treatment contributes to the efficiency of the naphtha reforming step. Other objects and advantages of the invention will appear during the course of the description hereinafter given.

In order to achieve the foregoing and related ends it is contemplated by my invention to pyrolyze butane at a high temperature to produce butylene, and to reform a naphtha to a substantial extent, and then to combine the hot pyrolysis products with the naphtha. The combined streams are then subjected briefly to relatively severe reforming conditions to enhance further the antiknock properties of the naphtha. I have found that when naphtha is reformed in the presence of light normally gaseous hydrocarbons, a higher reforming temperature may be used without excessive coke formation, and hence a higher octane product may be produced. During early stages of the naphtha reforming conversion, when severe temperature conditions have not been reached and while the more readily reformable fractions are being converted, there is no important advantage to be obtained by having light hydrocarbons present. It is for this reason that I admix pyrolysis products with naphtha which has already undergone substantially the usual extent of reforming, so as to make possible further conversion under especially severe conditions which normally are productive of excessive coke deposition.

Proper temperatures for butane pyrolysis lie in the vicinity of 1050° F. and higher, while naphtha reforming as ordinarily practiced employs temperatures between about 950° F. and 1025° F. It is contemplated by the invention that hot pyrolysis products, at a temperature of about 1050° F. or higher, shall be mixed with naphtha which has been reformed at about 1000° F. to 1025° F. Upon being commingled with the pyrolysis products, the naphtha is given a substantial instantaneous temperature increase, and during further heat treatment of the mixture as contemplated by the invention it is enabled to withstand the increased temperature without deposit-

ing excessive amounts of coke, by reason of the presence of the light normally gaseous pyrolysis products. Subsequent to this further heat treatment in accordance with additional features of my invention I recover high octane gasoline produced by the naphtha reforming operation; I also recover butylene produced by the pyrolysis together with C₄ hydrocarbon by-products of the reforming, including iso-butane. I subject the latter materials, augmented if desired with additional alkylatable C₄ hydrocarbons, to catalytic alkylation, whereby I produce further amounts of high octane gasoline.

A preferred embodiment of the invention will 15 now be described in detail with reference to the annexed drawing, which is a diagrammatic flow sheet. It is to be understood, however, that this embodiment is illustrative only, and in no way limits the scope of the invention.

In the drawing, naphtha which is to be treated 20 in accordance with the invention is taken from any suitable source and passed through line 1 into a preheating coil 3 located in the convection section of a furnace 2, and passes thence to a reforming coil 4 situated in the radiant section of the furnace. In traversing the latter two sections the naphtha is raised to and maintained for a time at a temperature which is preferably slightly higher than 1000° F., for example, 1020° F.

At the same time a stream of normal butane 25 which is to be pyrolyzed in accordance with the invention for the formation of butylene is withdrawn from a suitable source and passed through line 5, for admixture with recycled normal butane (derived from a subsequent step of the process) traversing line 6. The combined normal butane stream goes through line 6 into a preheater coil 7 situated in the convection section of furnace 2 and from thence enters a pyrolysis coil 8 situated in a radiant section of the furnace. Upon entering the pyrolysis coil the butane stream may be suitably at a temperature of approximately 900° F. and in traversing the pyrolysis coil is heated to a temperature which is preferably about 1050° F. to 1250° F. At this high temperature the normal butane is partially converted into butylene, the by-products being C₃ and lighter hydrocarbons. After traversing coil 30 the stream is admixed with naphtha from coil 4 and the commingled streams are then passed through a further soaking coil 9 in which a temperature of about 1025° F. to 1050° F. is maintained. During its traverse of this soaking coil further reforming of the naphtha takes place

with the result that the octane number thereof is substantially increased.

On leaving the soaking coil 9 the hot conversion products travel via line 11 into a bubble tower 12 wherein, by appropriate fractionation under reflux, any by-product material boiling above the gasoline range including polymer and tarry residue is separated and withdrawn as indicated by line 13 for disposal as desired. Gasoline fractions and normally gaseous hydrocarbons are taken overhead from bubble tower 12 via line 14 and are further fractionated in a debutanizer 15 from which gasoline fractions are withdrawn as indicated by line 16. The gasoline so withdrawn comprises chiefly the product of the reforming operation on the initial low octane naphtha. Hydrocarbons lighter than pentane are preferably wholly withdrawn in the overhead product from debutanizer 15 and passed via line 17 into depropanizer 18. The function of the latter column is to separate C₃ and lighter hydrocarbons as an overhead product for rejection from the process via line 19, leaving in the bottom product traversing line 21 only the C₄ hydrocarbons which are to be treated in further steps of the process. These C₄ hydrocarbons, comprising iso-butane, normal butane and butylene are transferred through line 21 to an alkylation unit 22 and are therein subjected in known manner to catalytic alkylation in the presence of a catalyst such as 96% sulphuric acid, whereby alkylation of the iso-butane with butylene is effected. Although appreciable quantities of iso-butane will normally be produced as a by-product of the naphtha conversion, the available butylene will ordinarily be more than sufficient in amount to react with all the iso-butane so produced, and it will therefore be desirable to supply additional iso-butane to the alkylation process from an extraneous source, as indicated by line 20. Normal butane and excess iso-butane pass unchanged through the alkylation reaction, the excess iso-butane being present as a result of the iso-butane recycling procedure described immediately below. As is well known, catalytic alkylation of iso-butane with butylene is advantageously accomplished in the presence of a substantial excess of iso-butane.

The gross product of the alkylation process is passed through line 24 to a de-isobutanizer 25 from which excess iso-butane in the gross product is withdrawn overhead and returned through line 23 to the alkylation zone. The quantity of iso-butane so recycled for the purpose of maintaining an excess thereof in the alkylation zone is constant and does not affect the net transfer of materials to and from the alkylation process. Materials heavier than iso-butane, consisting essentially of alkylate and normal butane, are withdrawn as a bottom product from the de-isobutanizer 25 and pass through line 26 to a debutanizer 27 wherein final separation of alkylate from lighter hydrocarbons is effected. The alkylate is withdrawn from the bottom of the debutanizer through line 28 and disposed of as desired while lighter materials, consisting essentially of normal butane, is returned through line 6 for admixture with the fresh feed normal butane entering line 3 as previously described.

As will be understood by those skilled in the art of hydrocarbon pyrolysis, the conversion of normal butane into butylene and lighter by-products is incomplete in a single pass through the pyrolysis coil. The maximum yield of butylene is ultimately obtained by continuous return of unconverted normal butane from the final separa-

tion in the debutanizer 27. The normal butane so returned will also include such normal butane as may be formed from the fresh feed naphtha as a by-product of the reforming operation.

5 Insofar as butylene yield is concerned, the most advantageous pressure at which to pyrolyze the normal butane is atmospheric. It is usually more economic to employ a moderate superatmospheric pressure, however, in order to reduce the volume 10 of the material and enable a smaller pyrolysis coil to be used. The reforming operation is best conducted at a pressure between about 500 and 1000 pounds per square inch. As a compromise 15 pressure suitable for both types of conversions, and in order to prevent polymerization as hereinafter discussed, I prefer to use 400 to 500 pounds in coils 8 and 9.

As is well known, the pyrolysis of butane to 20 form butylene is likely to be attended by more or less polymerization of the butylene after formation thereof. My invention is distinguishable from prior known processes to which it bears a superficial resemblance by the fact that polymerization is definitely not desired and is curtailed as far as possible by appropriately chosen operating conditions. So-called naphtha reversion processes as heretofore proposed have involved the use of pressures in excess of 1000 pounds per square inch and extended soaking 25 of naphtha-olefin mixtures at polymerizing temperatures after formation of the olefins by pyrolysis at higher temperatures. In such processes a complete conversion of olefins into polymers of the gasoline type is aimed at. Polymerization in the pyrolysis coil 8 is substantially 30 prevented by the maintenance of a more or less continuously rising temperature gradient therethrough and by the relatively low pressure. Polymerization in the soaking coil 9 is also 35 minimized by the relatively low pressure and by making the time of residence of the material therein relatively brief. The brevity of the soaking time of course limits the extent to which the naphtha can be further converted in the 40 soaking coil, but by accomplishing the major portion of the naphtha conversion prior to admixing pyrolysis products therewith, only the most difficult and coke-producing conversion 45 remains to be effected in the soaker. At the high temperature of the soaking coil the naphtha reforming reaction goes on relatively rapidly 50 as compared to the polymerization reaction sought to be avoided.

It is to be understood that arrangements other 55 than the one described herein for illustrative purposes may be devised within the scope of my invention, which is limited only by the following claims.

I claim:

60 1. A hydrocarbon conversion process which comprises subjecting a naphtha of low anti-knock value to a thermal reforming treatment, separately subjecting normal butane to a thermal treatment at a pressure not substantially 65 higher than 500 pounds per square inch at a temperature higher than that employed in said naphtha reforming treatment to convert said normal butane to butylenes and lighter hydrocarbons, the reaction time in said butane treatment being restricted to minimize polymerization reactions, mixing the hot products of said thermal conversion treatments, subjecting the resulting mixture to further thermal treatment at a pressure not substantially higher than 500 70 pounds per square inch at a temperature higher 75

than that employed in said naphtha reforming treatment and above 1000° F., cooling the mixture to terminate said last-mentioned thermal treatment prior to any substantial polymerization of olefins formed in said thermal treatment of butane, separating from the reaction products a low boiling fraction containing butylenes and unreacted normal butane, subjecting said fraction containing butylenes and normal butane to alkylation treatment to effect alkylation of butylenes with an iso-paraffin hydrocarbon, fractionating the products of alkylation to separate therefrom a fraction essentially consisting of normal butane, and recycling said normal butane fraction to said thermal treatment of normal butane.

2. A hydrocarbon conversion process which comprises subjecting a naphtha of low anti-knock value to a thermal reforming treatment, separately subjecting normal butane to a thermal treatment at a pressure not substantially higher than 500 pounds per square inch at a temperature higher than that employed in said naphtha reforming treatment to convert said normal butane to butylenes and lighter hydrocarbons, the reaction time in said butane treatment being restricted to minimize polymerization reactions, mixing the hot products of said thermal conversion treatments, subjecting the resulting mixture to further thermal treatment at a pressure not substantially higher than 500 pounds per square inch at a temperature higher than that employed in said naphtha reforming treatment, and above 1000° F., cooling the mixture to terminate said last-mentioned thermal treatment prior to any substantial polymerization of olefins formed in said thermal treatment of butane, separating from the reaction products a low boiling fraction containing butylenes and unreacted normal butane, combining said fraction containing butylenes and normal butane with isobutane, subjecting the resulting mix-

ture to alkylation conditions to effect alkylation of butylenes with isobutane, fractionating the alkylation reaction products to separate therefrom a fraction consisting essentially of normal butane, and recycling said normal butane fraction to said thermal treatment of normal butane.

3. A hydrocarbon conversion process which comprises subjecting a naphtha of low anti-knock value to a thermal reforming treatment, separately subjecting normal butane to a thermal treatment at a temperature higher than that employed in said naphtha reforming treatment and at a pressure not substantially higher than 500 lbs. per square inch to convert said normal butane to butylenes and lighter hydrocarbons, the reaction time in said butane treatment being restricted to prevent substantially the occurrence of polymerization reactions, mixing the hot products of said thermal conversion treatments, subjecting the resulting mixture to further thermal treatment at a temperature higher than that employed in said naphtha reforming treatment and above 1000° F. and at a pressure not substantially higher than 500 lbs. per square inch, cooling the mixture to terminate said last-mentioned thermal treatment prior to any substantial polymerization of olefins formed in said thermal treatment of butane, separating from the reaction products a low boiling fraction containing butylenes and unreacted normal butane, transferring said fraction containing butylenes and normal butane to an alkylation process, treating said last-mentioned fraction in said alkylation process to alkylate said butylenes with an isoparaffin hydrocarbon and separate a fraction essentially consisting of normal butane, and recycling said normal butane fraction to said thermal treatment of normal butane.

FRANK J. JENNY.
